UNITED STATES PATENT OFFICE.

ANTON F. JELEN, OF KANKAKEE, ILLINOIS.

EXCAVATOR.

Application filed October 9, 1925. Serial No. 61,538.

This invention relates to excavators of that type intended more particularly for use in digging ditches or trenches and in which the digging operation is performed by drawing the shovel or bucket toward the source of power. The object of the invention is to provide an excavating apparatus of few parts which will be efficient in operation and in which the bucket may be automatically dumped and the load delivered at the point desired. One embodiment of the invention is illustrated in the accompanying drawings and will be hereinafter fully described, the novel features being particularly pointed out in the appended claims.

In the drawings:

Figure 1 is a side elevation of an excavator embodying my improvements;

Figure 2 is a section on the line 2—2 of Fig. 1;

Figure 3 is a section on the line 3—3 of Fig. 1;

Figure 4 is an enlarged sectional elevation more particularly showing the mounting of the bucket;

Figure 5 is a section on the line 5—5 of Fig. 4;

Figure 6 is a section on the line 6—6 of Fig. 4; and

Figure 7 is a detail section.

The excavator embodying my invention includes a main boom 1 and a supporting frame 2 which are mounted upon the end of a traveling turntable 3 which forms a part of the engine structure, the engine being driven by steam and housed within a shed 4 which also encloses the boiler and other parts directly connected with the engine. As is usual in this type of machines, the operator remains within the shed 4 and controls the working parts by manipulation of levers and drums located within the shed and suitably geared to the engine. The shed is generally mounted upon a tread mechanism 5 of the chain type whereby it may be easily caused to travel over roads or streets under its own power without injury to the surface over which it moves. The frame 2 and the main boom 1 are connected with the turntable through intermediate connecting plates 6 which, as shown most clearly in Fig. 1, are of a general triangular form and each has one corner mounted upon a cross rod 7 which is carried in the projecting ends of the arms of the turntable 3. The upper corners or angles of these connecting plates are given a proper form, as shown at 8, whereby they will fit between the flanges of the side members of the frame 2 and are rigidly secured thereto by rivets or otherwise. The side members of the frame 2 are channel bars of proper dimensions and are properly connected by brace members 9, as shown most clearly in Fig. 3. Carried by and between the lower ends of the frame side members is a rod 10 on which is mounted a pulley 11 which constitutes a guide for the drag line 12 as will hereinafter more fully appear. The lower forward corners or angles of the connecting plates 6 carry a rod 13 upon which the main boom 1 is pivotally mounted, the boom being equipped at its lower end with brackets 14 which encircle the rod, as will be understood. Reinforcing plates or brackets 15 may be provided at the inner sides of the connecting plates and of the frame 2 so as to reinforce the lower end of the upright frame and also lend additional support to the rod 10. The pivot rods 7 and 13 are each formed with recesses or notches, as indicated at 16, (Fig. 7) and locking plates 17 are secured upon the outer sides of the connecting plates to fit within said notches and thereby prevent rotation of the respective rods and also hold them against endwise movement so that wear upon the parts is minimized and accidental detachment of the connected elements is avoided, minimizing danger to the workmen. The frame 2 is inclined slightly upwardly and forwardly, as shown in Fig. 1, and the upper end of the frame is connected with the roof of the shed 4 by supporting bars 18 having their inner ends firmly secured to the roof of the shed and their outer ends fitted between the upper extremities of the side bars of the frame, a rod 19 being inserted through the ends of the frame and of the said holding bars 18, as will be understood. The rod 19 is held against rotation and against endwise movement by lock plates 20, corresponding in all respects to the lock plates 17. Between the ends of the securing bars or arms 18, a pulley 21 is mounted upon the rod 19, and this pulley forms a guiding support for the hoisting line 22, as will hereinafter more fully appear.

The main boom 1 consists of a pair of channel bars of proper dimensions to possess the necessary strength, and these channel bars converge somewhat toward their outer ends, as shown in Fig. 2. In the outer ends

of the said channel bars is secured a rod 23, corresponding in all respects to the rods 7, 13, and 19, and held against rotation and against endwise movement in the same manner. The top boom 24 passes between the outer extremities of the members of the main boom and also consists of a pair of channel bars, as shown most clearly at 25 in Fig. 2. The channel bars 25 are connected by braces 26 provided in such number and at such points as may be deemed most desirable, and the side members of the main boom are likewise connected by plates 27 and braces 28 so that a very strong rigid structure is provided. A bearing block 29 is provided on the inner or rear side of each channel bar 25 and is firmly secured to the said channel bar by a U bolt 30 passing around the bearing block and through the flange webs of the bar, and secured by nuts bearing against the outer or front face of the adjacent bracing plate 26, as shown most clearly in Fig. 4. The bearing blocks 29 encircle the rod 23 so that the top boom may have pivotal movement with respect to the main boom. In the upper end of the top boom is mounted a rod 31 which is secured against rotation and endwise movement in the same manner as the rods 7, 13, 19 and 23, and upon this rod 31 is mounted a pulley 32 about which the hoisting line 22 is trained. The hoisting line is also trained around a small idler or guide pulley 33 mounted on the front side of the frame 2, near but below the upper end thereof, by means of brackets 34 which are secured rigidly upon the frame and have forwardly projecting ears or lugs at their inner ends in and between which the pulley 33 is rotatably mounted, this arrangement utilizing the lugs or ears as guards to prevent the hoisting line or cable jumping from the pulley. For a like purpose, guard plates 35 are mounted upon the rod 31 at the sides of the pulley 32 and similar plates may be provided at the sides of the pulley 21. The hoisting line extends outwardly or forwardly from the pulley 33 and has its end secured firmly to the main boom while the opposite end of the line, passing downwardly from the guide pulley 21 within the shed 4, is secured to and wound upon one of the engine-driven drums.

Secured to the outer end of the top boom is a bracket 36 which is shown most clearly in Fig. 5. This bracket has an intermediate portion extending laterally from the end of the boom and has one end portion 37 projecting outwardly parallel with the boom while its opposite end portion 38 fits against the inner side of the side bar of the boom and is riveted thereto. In Figs. 4 and 5, I have indicated the bracket as having a central portion 39 bridging the interior of the top boom, but it will be understood that this central portion may be omitted and a pair of brackets each consisting of the portions 36, 37 and 38 may be employed. Carried by the terminals 37 of the bracket is a rod 40 upon which the bucket is pivotally mounted. As shown most clearly in Fig. 6, the main body 70 of the bucket comprises a bottom plate 41, side plates or walls 42, and a back wall 43 which may be integrally formed, the height of the bucket being slightly greater at its open front side than at its closed back, as 75 will be understood upon reference to Fig. 1, and the width of the bucket likewise gradually decreasing from the open side to the back wall 43. This form has been found highly desirable inasmuch as the load taken up by the bucket is very effectually and cleanly discharged and the operation is expedited very appreciably over forms previously employed. The digging member or mouth portion of the bucket comprises a 85 band 44 which is shaped to conform to the open side of the bucket and is firmly riveted to the same against the outer face thereof. This digging member has its central edge portion projected somewhat relative to its side portions, as shown at 45 in Fig. 4, and to the said edge portions of the digging member are secured excavator teeth 46 which may be of any approved form. Scraping or excavating teeth are also secured to the sides 95 of the digging member so as to engage the sides of the ditch and provide clearance for the bucket whereby the withdrawal of the bucket from the ditch will be facilitated. Triangular reinforcing plates 48 are provided at the inner sides of the ends of the digging member 44 and have their inner edges overlapping and rigidly secured to the edges of the side walls 42 of the main bucket body. Filler plates 49 are inserted between the 105 bracing plates 48 and the sides of the digging member, and the bracing plates and the filler plates are firmly united, by riveting or otherwise, with the side portions of the digging member. The end portions of the sides 110 of the digging member and the bracing plates 48 are each provided with projecting corners 50 extending beyond the adjacent edges of the filler plates 49 and between these projecting corners of the digging member and the reinforcing plates are received the ends of a draft bail 51 which is pivotally connected to the bucket by pins or rivets 52 inserted through its ends and through the said bracing reinforcing plates and the digging member, as shown clearly in Figs. 4 and 6. The end of the drag line 12 is firmly attached to the said bail 51, and, from the bail, the drag line passes over a pulley 53 which is mounted upon the main boom between the ends of the same, the drag line passing over the said pulley 53 and under the pulley 11 and thence to a drum within the shed 4 upon which it is wound and which is driven by the engine. 115 120 125 130

Rigidly secured upon the back wall 43 of the bucket at the upper edge thereof are lugs or brackets 54 and pivoted to and between the said brackets is one end of a dumping arm. This dumping arm extends from the bucket to the top boom 24 and consists of a pair of flat bars or metallic straps 55, pivoted at their outer ends to the lugs 54, and a bar 65 which is pivoted between its ends to the inner ends of the bars 55 and, at its inner end, is equipped with a pair of rollers 56 which run upon a track 57 carried by the said top boom and consisting of a shallow U-shaped bar or plate or pair of such bars or plates having their ends secured to the bracing plates 26 and their intermediate portion housed within the boom, as shown in Fig. 4. The rollers 56 are mounted upon a pin or rod 58 which is carried by a bearing block 59 secured to a coupling plate 60 which is riveted upon the bar 65 and extends beyond the end of the same to play within the top boom. To the extremity of this coupling plate 60 one end of a chain 61 is attached and the opposite end of the chain is secured in any convenient manner to a bracing plate 27 upon the main boom, or otherwise anchored upon the boom. The bar 65 is T-shaped in cross section through the greater portion of its length, the stem of the T fitting between the bars 55 with the head overlying the latter. The head of the T terminates short of the outer end of the stem thereof, as will be understood upon reference to Fig. 4, and the extremity of the stem is extended laterally from between the bars 55, as at 66. To the buttoned extremity 66 is secured a cable 67 which extends over a guide roller 68 on the top boom, below the pulley 32, and thence to and over a guide roller 69 on the frame 2, the end of the cable being attached to a hand lever, as 70, within the shed 4. Normally, the cable 67 is slack and the overlying relation of the bar 65 to the bars 55 prevents relative movement of these members about the pivot 71 so that they constitute a rigid lever.

It is thought the operation of the machine will be readily understood from the foregoing description, taken in connection with the accompanying drawings. If the hoisting line be played out while tension be maintained upon the drag line, the boom 1 will swing downwardly with the top boom and the bucket in the position shown in full lines in Fig. 1. After the bucket reaches the bottom of the ditch or the point where further digging is to be done, the hoisting line is permitted to slacken while a pull is exerted upon the drag line. The bucket will thus be drawn toward the engine and will take up a portion of the surface over which it moves so that it will be quickly filled. When it is filled, the pull upon the drag line is stopped and pull is then exerted upon the hoisting line while maintaining the tension upon the drag line, the main boom being thus caused to swing upwardly so that the parts will return to the position indicated by full lines in Fig. 1 and by dotted lines in Fig. 4. The drag line is then slackened and pull is continued upon the hoisting line, the result being that the top boom is caused to move pivotally about the end of the main boom to the position shown in full lines in Fig. 4, the slack in the chain 61 being thereby removed and the end of the dumping bar or arm 55 being caused to move toward the pivot of the top boom so that it will exert a pull upon the back of the bucket and invert the same, as shown in full lines in Fig. 4. The load taken up by the bucket will thus be dumped automatically. The automatic dumping of the load is advantageous when the excavated material is to be deposited at the side of the ditch, as it permits the machine to be operated at very high speed. When the material is to be hauled away, the cable 67 is brought into use in order to dump the load directly into a vehicle. Instead of slackening the drag line 12 as the bucket rises, tension is maintained thereon or even increased so that swinging of the top boom is prevented. When the bucket is at the proper height and has been brought into position over the vehicle by lateral movement of the main boom, a pull is exerted upon the cable 67 whereby the bar 65 will be swung upwardly about the rod 58 as a center. As a result, the bars 55 tend to assume a perpendicular position and the bucket is tilted to discharge its contents. Upon release of the cable 67, the weight of the bucket returns the parts to the normal position.

It will be understood that the entire apparatus is moved in a horizontal plane so that the bucket will be carried to a point at the side of the ditch before dumping its load, and that a reverse movement is imparted to the entire apparatus to bring the bucket into position over the ditch in order to take up a second load. In the operation of the excavating and dumping apparatus, however, the operator is required to manipulate only two lines and experience has shown that the apparatus can be operated at a very much higher speed than is possible with any previous apparatus known to me and will at all times operate in a highly efficient manner. When the bucket is in digging position, about two-thirds of the entire weight of the apparatus is carried by the bucket so that it will be held firmly to its work and will readily penetrate and take up the material to be removed. In actual practice, the bucket has been drawn easily through rocky formations and has actually dug through solid strata of sand stone. The automatic dumping of the

bucket does not require the operator to release any latches or manipulate any cables or connections other than the cables or lines which are employed to lower the bucket into a ditch, drag it along the ditch and remove it from the ditch.

Having thus described the invention, I claim:

1. An excavating apparatus comprising a main boom mounted for raising and lowering movement, a top boom pivotally mounted at the free end of the main boom, a bucket pivotally mounted at the lower end of the top boom, operating cables attached to the main boom and the bucket respectively and trained about the top boom, a dumping arm pivotally connected with the bucket at one end and engaged at its opposite end with the top boom to travel longitudinally thereof, and a connection between the main boom and the last-mentioned end of the dumping arm.

2. An excavating apparatus comprising a main boom mounted for raising and lowering movement, a top boom pivotally mounted at the free end of the main boom, a bucket pivotally mounted at the lower end of the top boom, operating cables attached to the main boom and to the bucket respectively and trained about the top boom, a dumping arm pivotally connected with the bucket at one end and having its opposite end arranged to travel along the top boom, and a flexible connection between the said dumping arm and the main boom.

3. In an excavating apparatus, the combination of a main boom mounted for raising and lowering movement, a top boom pivotally mounted at the free end of the main boom, a U-shaped track within the top boom extending longitudinally of the same, a bucket pivotally mounted upon the lower end of the top boom, a dumping arm pivoted at one end to the bucket and having its opposite end arranged to travel along the track in the top boom, and a flexible connection between the said end of the dumping bar and the main boom.

4. In an excavating apparatus, the combination of a main boom mounted for raising and lowering movement, a top boom pivotally mounted at the free end of the main boom, a relatively depressed track within the top boom below the pivot of the same, a bucket pivoted to the lower end of the top boom, a dumping bar pivoted at one end to the bucket and having its opposite end disposed within the top boom, rollers carried by the said end of the dumping bar to travel on the said track and limited in their movement by the ends of the track, a chain attached at one end to the last-men-

tioned end of the dumping bar and anchored at its other end upon the main boom, a hoisting line connected with the main boom for raising and lowering the same and arranged to move the top boom pivotally, and a drag line connected with the bucket whereby to effect dumping of the bucket when the top boom is moved pivotally.

5. In an excavating apparatus, the combination of a main boom, a top boom pivoted to the free end of the main boom, brackets secured to the lower end of the top boom, a bucket comprising a body and a digging member arranged at the open side of the body, reinforcing plates secured to the inner faces of the body and the said digging member, the digging member and the reinforcing plates having projections on their free edges, pivotal connections between the upper ends of the reinforcing plates and the brackets on the top boom, a bail having its ends pivoted to and between the projections on the reinforcing plates and the digging member of the bucket, a drag line attached to said bail, a hoisting line attached to the main boom and operatively engaged with the upper end of the top boom, and means cooperating with the bucket and the top boom to dump the bucket upon manipulation of the hoisting line and the drag line.

6. An excavating apparatus comprising a main boom, means for raising and lowering said boom, a top boom pivotally mounted on the main boom, a bucket pivotally mounted at the lower end of the top boom, a drag line connected to the bucket, a dumping arm extending between the bucket and the top boom and including a member pivoted to the bucket and a member pivoted between its ends to the first member and having its inner end connected with the boom, the second member having its outer portion normally overlying the first member, and an operating cable connected to the outer end of the second member.

7. An excavating apparatus comprising a main boom, means for raising and lowering said boom, a top boom pivotally mounted on the main boom, a bucket pivotally mounted at the lower end of the top boom, operating cables connected to the bucket and the main boom respectively, a foldable dumping arm extending between the bucket and the top boom, means for normally holding the dumping arm on a straight line between the bucket and the top boom, means for effecting travel of the dumping arm along the top boom, and an operating cable connected to the outer end of the dumping arm.

In testimony whereof I affix my signature.

ANTON F. JELEN. [L.S.]
